UNITED STATES PATENT OFFICE.

NATHAN HARRIS, OF JAMAICA PLAIN, MASSACHUSETTS, ASSIGNOR OF ONE-THIRD TO
KARL M. GOLDSMITH, OF NEW YORK, N. Y., AND ONE-THIRD TO LOUIS HARRIS,
OF BOSTON, MASSACHUSETTS.

COAT-COLLAR.

977,865.

Specification of Letters Patent.

Patented Dec. 6, 1910.

Application filed October 25, 1909. Serial No. 524,758.

To all whom it may concern:

Be it known that I, NATHAN HARRIS, a citizen of the United States of America, and a resident of Jamaica Plain, in the county of 5 Suffolk and State of Massachusetts, have invented certain new and useful Improvements in Coat-Collars, of which the following is a specification.

This invention relates to garments such as 10 coats, overcoats, and similar articles of wearing apparel and has for its particular object the provision of a means whereby the garment may be used in two different forms, in one case showing a lapel and turn-over collar while in the other case the coat front is 15 buttoned up and a military collar is formed. In each case the same face of the collar, whether used turned over or as a military collar, is outermost and in each case the fold 20 of the collar at the rear of the neck is substantially the same, these two folds diverging from a central point toward the front of the collar.

The invention consists in certain novel 25 features of construction and arrangement of parts which will be readily understood by reference to the description of the drawings and to the claims hereafter given.

Of the drawings: Figure 1 represents a 30 front view of the upper portion of a coat having applied thereto a collar embodying the features of the present invention and indicated as a turn-down collar. Fig. 2 represents the same coat buttoned up to the neck 35 and the collar folded to form a stand-up or military collar. Fig. 3 represents an enlarged view of one end of the coat collar, the lapel and the fastening tab interposed between said collar and lapel. Fig. 4 represents a portion of the body of the coat, 40 before it is formed into a garment. Fig. 5 represents one end of the collar, before being formed into a garment. Figs. 6 and 7 represent respectively outer and inner parts 45 of the fastening tab. Fig. 8 represents a section through the front portion of the turned-over collar, the cutting plane being on line 8—8 on Fig. 1. Fig. 9 represents a section through the front portion of the 50 military collar, the cutting plane being on line 9—9 on Fig. 2. Fig. 10 represents a section through the collar at the back of the neck, the cutting plane being on line 10—10 on Fig. 1. Fig. 11 represents a section through

the body portion and the fastening tab, the 55 cutting plane being on line 11—11 on Fig. 3. Fig. 12 represents an inside view of a portion of the collar before being made into a garment and folded over as in use for a turn-over collar, and Fig. 13 represents the 60 same collar folded over as in use for a stand-up or military collar.

Similar characters designate like parts throughout the several figures of the drawings.

In the drawings, 10 represents the body 65 portion of a coat provided with a lapel 11 adapted to be folded over on the line 12 (see Fig. 4) into the position indicated by the dotted lines 13 on said figure. Secured to 70 the inner face of the body portion 10 is the usual facing 14. The upper end of the lapel is slightly below the neck edge 15 of said body portion as clearly indicated in Fig. 4 of the drawings. This leaves an edge 16 75 parallel with the front edge of the body portion to which is secured the edge 17 of the fastening tab 18. The tab 18 has secured thereto a facing tab 19 having an elongated tapered curved end 20 the lower edge of 80 which is secured to the upper edge of the facing 14. The upper edge of this curved end 20 is secured to the edge 21 of the inner facing 22 of the collar, the outer portion 23 of which is cut as shown in Fig. 5 of the 85 drawings, it being understood that the opposite end of the collar is the reverse of the portion shown in said figure. The edge 23* of the outer piece 23 is secured to the neck edge 15 of the body portion. The inner 90 facing 22 and the outer piece 23 of the collar are stitched together in the usual manner and are stretched and formed to give the required curvature to the neck.

In practice, between the inner and outer 95 facing of the collar a stiffening member of canvas is inserted but for convenience is omitted from the drawings as this forms no part of the present invention. This stiffening member is also omitted from the 100 sectional views so as not to complicate these figures.

The effect of the curved tapered end 20 of the facing when stitched to the collar facing and the lapel facing is shown clearly 105 in Figs. 1 and 3 of the drawings, giving a certain character to the coat which is of a pleasing effect and dissimilar from the usual

garments of this class. It will be observed by reference to these figures that the fastening tab 18 and 19 when stitched together at their outer ends are disconnected for a certain distance from the upper edge of the lapels 11 and from the ends of the collar 22 and 23, the inner end 24 of the slits being sufficiently distant from the outer edge 25 of the collar to permit said collar to be folded over on the line 26 (see Fig. 5) to form the military collar while permitting the fastening tabs 18—19 to be folded over in a different direction to secure the upper ends of the body portion together as indicated in Fig. 2 of the drawings. In doing this, one of the tabs is laid flat upon the under portion of the coat while the tab upon the upper portion of the coat is secured by means of the button hole 27 to a button 28 secured to the outer face of the body portion beneath the collar, all as clearly shown in Figs. 2 and 9 of the drawings.

When the garment is used with a turn-over collar the fastening tabs 18 are preferably secured to the body portion by means of buttons 29 on the outer face of said body portion. It is obvious from an inspection of the drawings that the fold of the collar in each case is substantially the same at the rear of the neck and that the outer face of the collar is always exposed whether it is used in the turn-over style or in the military style. Obviously this is of considerable advantage as it leaves the collar free from wrinkles and folds which interfere with the comfort of the wearer and the appearance of the garment.

When the collar is used in the military style, it is folded over substantially on the line 26 between the ends 24 of the slits between the tab portions 18 and 19 and the end of the collar 22 and 23, and the elongated end 20 forms the "stand" therefor.

This makes a very convenient garment which may be worn in the usual manner and when the weather becomes disagreeable may be buttoned up to the neck and a collar secured in military style protecting the wearer against wet and cold without causing any other inconvenience.

It is believed that the construction and

many advantages of the invention will be fully understood from the foregoing.

Having thus described my invention, I claim:

1. In a device of the class described, the combination with the body portion of a coat or similar garment; of a collar the ends of which are a short distance from the ends of the lapels; and curved members interposed between said collar and the body portion of the coat adapted to serve as a stand for said collar when it is folded over upon the upper edge of said curved portion to give a military effect thereto. 65

2. In a device of the class described, the combination with the body portion of a coat or similar garment; of a collar the ends of which are a short distance from the ends of the lapels; and curved members interposed between said collar and the body portion of the coat adapted to serve as a stand for said collar when it is folded over upon the upper edge of said curved portion to give a military effect thereto, said curved portion terminating in a tab interposed between the ends of said collar and said lapels but separated therefrom for a short distance at each edge. 70

3. In a device of the class described, the combination with the body portion of a coat or similar garment; of a collar the ends of which are a short distance from the ends of the lapels; and curved members interposed between said collar and the body portion of the coat adapted to serve as a stand for the collar when it is folded over to give a military effect, one of said members being provided with a securing device and both of said members terminating in tabs interposed between the ends of said collar and said lapels, one of which tabs is provided with a member adapted to co-act with said securing device to retain said curved members upright. 85

Signed by me at 4 Post-Office Sq., Boston, Mass., this 21st day of October, 1909.

NATHAN HARRIS.
